UNITED STATES PATENT OFFICE.

JOSEF KELLNER, OF BROOKLYN, AND SIDNEY WORMS, OF NEW ROCHELLE, NEW YORK,
ASSIGNORS TO FRANKLIN KNITTING MILLS, A CORPORATION OF NEW YORK.

PROCESS OF KNITTING BIAS-LACE KNITTED NECKTIES.

1,072,734.

Specification of Letters Patent.

Patented Sept. 9, 1913.

Application filed March 11, 1913. Serial No. 753,650.

To all whom it may concern:

Be it known that we, JOSEF KELLNER, a subject of the Emperor of Germany, and SIDNEY WORMS, a citizen of the United States, residing, respectively, at Brooklyn, in the county of Kings and State of New York, and New Rochelle, in the county of Westchester and State of New York, have invented certain new and useful Improvements in Processes of Knitting Bias-Lace Knitted Neckties, of which the following is a specification.

This invention relates to the process of knitting, and more particularly to the knitting of neckties and scarfs, the object of the invention being to provide an improved process or method of knitting neckties and scarfs, whereby the tie may have a stripe or stripes therein, having a lace effect on a true or substantially true bias, and may also have therein at one or both sides of such lace formed stripe, a stripe or stripes each of one or more colors, all of which stripes may be fed or shot into the tie at intervals and which necktie may have a narrow neck portion merging into a gradually widened flaring end or ends and the body of which tie may be knitted of one or several colors to give an iridescent or accordion effect.

A further object of the invention is the provision of an improved process whereby a knitted tie is formed with its thread loops on a bias, and which tie may have therein likewise on a bias a stripe or stripes of a lace formation, or other design and at one or both sides thereof may have a stripe or stripes of a contrasting color or colors also located on a bias.

In the drawings accompanying and forming a part of this specification, Figure 1 is a cross-sectional view of a part of one form of a flat knitting machine, which may be provided for carrying out this improved process; Figs. 2, 3, 4, and 5, illustrate a portion of the needle beds, one of which is shown in different positions; Fig. 6 a pair of needles; Fig. 7 one of the cam locks for shifting the needles; Fig. 8 is a sectional view of one form of tensioning means; and Fig. 9 is a view of a necktie illustrating the diagonal stripes of different design, shown more clearly however in Fig. 8, where the

fabric is illustrated passing through the differential tensioning means.

Similar characters of reference indicate corresponding parts in the different figures of the drawing.

For carrying out this process we provide a flat knitting machine comprising a pair of inclined needle beds 2 and 8 suitably supported by standards 4, one only of which is shown, and which needle beds carry two sets of needles 5 and 6 shiftable in the usual way by a shiftable carriage 7 having cam-locks 8. Located below the inclined beds is a suitable differential tension or take up device for giving proper tension to the work as it is knitted. This tension means in the present instance comprises a roll 9 suitably mounted upon a shaft 10 and a series of rolls mounted upon a shaft 12. In the present instance four of these rolls are shown, one of which, as 13, is located directly upon the shaft, while the other three, as 14, 15 and 16, are each provided with a tubular shaft, as 17, 75 or 18, or 19, one located within the other, and on the ends of these tubular shafts 17, 18 and 19 are located gears 20, 21 and 22, and on the end of the shaft 12 is also fixed a gear 23, these gears being so proportioned that the roll 16 will have the smallest gear, while the roll 15 will have the next largest, and so on, so that the greatest speed will be given to the roll 16. For operating these spur gears a stud shaft 24 is provided, 85 which may be driven from any suitable source of power and carries in the present instance a series of four gears 25, 26, 27 and 28 of gradually increasing diameter meshing with the gears 23, 22, 21 and 20 respectively. Thus it will be observed that the greatest tension will be placed upon that side of the fabric engaged by the roll 16 by reason of its greater speed. Of course it will be understood that the position of the gears 95 could be changed so that the greatest tension could be placed upon the opposite side for the purpose hereinafter described.

In carrying out this process the knitting is started with a certain width in the machine, and by gradually throwing out of operation certain needles on one side the tie will be tapered on one side, while it is relatively straight on the other side until the

neckband is reached, which is knitted straight, after which, by gradually throwing into operation certain needles on one side, the opposite end of the tie will be gradually flared on one side and knitted straight on the other, thus to provide a tie having a pair of wide flowing flaring ends. By using threads of different colors an iridescent or accordion effect may be given to the tie by 5 reason of the fact that the tie will have longitudinally thereof alternate colors or rows or wales of stitches. At intervals along the tie stripes of a peculiar design are formed, and in some instances this design has much 10 the appearance of a lace effect, this being obtained during the feeding into the tie of threads preferably of another color or colors and by the particular manipulation of the needle beds, and also in some instances, 15 according to the style of the lace work, by the particular manipulation of the needles. These stripes in the present instance by means of this improved process are located on a true or substantially true bias, and so 20 far as we are aware it has never heretofore been possible to knit such a necktie with stripes of this character on a true bias. At each side of these stripes in the form 25 of necktie shown, there is provided one or more stripes of a contrasting color or colors 30 to the body of the tie and if desired to the intermediate lace formed stripes, and these stripes are likewise located on a true bias.

To accomplish this process the rear needle 35 bed 2 is provided with means which may be automatically operative or operated by hand, for racking or shogging it step by step during the knitting of the tie whereby the stripes will be located on a true bias 40 when the tie is completed. In the present instance the rear needle bed 2 is shown racked by hand, and for this purpose it is provided with a projection 30 having a stud 31 movable in a cam groove 32 of a cam 33 45 mounted on a short shaft 34 carrying a handle 35, on the shifting of which the rear needle bed 2 will be racked or shogged to the left as shown in Figs. 2 and 3 or to the right as shown in Figs. 4 and 5, and by 50 racking the needle bed in the manner shown the positions of the rear needles are changed with relation to the front needles; that is to say, when the rear needle bed, which is normally in the position shown in Fig. 5, 55 is racked to the left as shown in Figs. 2 and 3 each rear needle 40 will work opposite its companion front needle but on the left side thereof, while when the needle bed is racked back to the right as shown in Figs. 60 4 and 5 each rear needle 40 will work opposite its companion needle but on the right side thereof when the slippable carriage carrying the cam-locks is shifted across the needle bed to project and return the needles 65 in a manner which is well understood. This

racking or shogging of the rear needle bed is to the right, prior to the carriage moving to the right, or as the carriage is moved to the right but prior to its engagement with the needles to be operated, and the 70 bed is racked back to the left prior to the movement of the carriage to the left, or during such movement but prior to its engagement with the needles to be operated. By starting the racking movement for instance 75 to the right, the stripes will be located on one bias or in one direction, but by reversing this and starting the racking movement to the left when the knitting operation is started the position of the stripes will 80 be reversed; that is to say by racking to the right, in Fig. 8, the stripes are shown with the left hand ends thereof higher than the right hand ends, but, as hereinbefore stated, when the racking movement is reversed 85 on the starting of the knitting operation the right hand ends of the stripes will be located higher than the left hand ends thereof, so that the direction in which the stripes may run is determined by the 90 direction of racking movement which is first given to the bed, either to the right or to the left, as the first course of knitting is started. If the racking movement is first given in one direction then the tension upon 95 the work will be upon one side, but if the racking movement is first given in the opposite direction then the tension must be so arranged that it will be upon the opposite side. In the present improvement the 100 stripes are located with the highest ends at the left and therefore the tension is so arranged that the greatest tension will be given upon the left side of the work. If, the position of the stripes, however, were 105 reversed in the manner hereinbefore stated, then the tension would likewise have to be reversed so that the greatest tension would be given the work upon the right side. To form a bias stripe of a contrasting color, for 110 instance running in a direction opposite to that shown in Fig. 9, but of a solid form as distinguished from a lace or open mesh form, the rear needle bed is racked or shogged one needle to the left, for instance 115 from its normal position shown in Fig. 5 to the position shown in Fig. 2, just prior to a row of stitches being formed and then prior to a succeeding row of stitches being 120 formed the needle bed is shogged to the right or back to its normal position as shown in Fig. 5, and so on. This manner or way of racking or shogging the needle bed will during the feeding of a different colored thread into the work form a solid stripe located on a bias across the work, and the foregoing manner in which the needle bed is racked or shogged is also the manner in 125 which the needle bed is racked or shogged during the formation of the whole fabric 130

on a bias. When, however, it is desired to form one style of lace or open mesh work stripe, (the various styles thereof being determined by the withdrawal of certain needles, that is to say the more needles that are withdrawn the more open will be the mesh), the rear needle bed is racked or shogged in a different way or manner, that is to say, prior to a row of stitches being formed the rear needle bed is first racked or shogged from its normal position shown in Fig. 5 to the position shown in Fig. 2, this being one needle or one step, and then after completing a round of stitches, that is two courses of stitches, it is racked or shogged another needle or another step as shown in Fig. 3 and then in the same manner the needle bed is racked or shogged back to its normal or original position as shown in Fig. 5, step by step, so that by this last procedure a different kind of stripe from that shown as a continuous or solid color stripe is obtained, such stripe having a lace effect, and located on a bias. After the formation of this stripe and when it is desired to form another stripe at the side thereof if this is found desirable the rear needle bed is racked or shogged in the same manner as shown in Figs. 2 and 5.

When the carriage is moving in one direction the front bank of needles 41 will cast off and complete stitches, while the rear bank 40 only make loops. While however the needles are out of engagement with the carriage cam-locks, the rear needle bed is racked in the manner hereinbefore described. During one movement of the carriage in one direction such carriage will pass over the needle beds and both front and rear needles will cast off, completing twice, we apprehend, the number of stitches in this stroke as in the previous one, and when the carriage cam-locks are out of engagement with the needle butts, the rear needle bed may be racked or shogged. In other words during the process of knitting while the carriage cam-locks are out of engagement with the needle butts, the rear needle bed in the present instance is first racked or shogged in one direction as to the left and then racked or shogged in the opposite direction as to the right, Figs. 2 and 5, to form the ordinary continuous stripe, but when the lace design stripe is formed then the carriage intermediate its movement and while the cam-locks are out of engagement with the needle butts, is first racked to the position shown in Fig. 2 and then further racked another step shown in Fig. 3 and then this is reversed, as shown in Figs. 4 and 5.

In knitting the tie, it is started with a certain width in the machine, as hereinbefore stated, as for instance it is started with the greatest width, as at 50, the triangular portion thereof being subsequently formed by

cutting and overedging the tie, and by constantly racking or shifting in the manner hereinbefore described the rear bed first one way and then the other if the solid continuous stripe is to be formed, that is alternately or by racking it step by step a plurality of times to the left, and then reversing this a plurality of times to the right if a different form of stripe is to be made, as for instance a lace effect, and by placing the left side of the tie under tension, by reason of the take up mechanism shown the result is the location of true bias stripes of different color or colors in the manner shown in Fig. 8, and by gradually throwing out of operation certain needles on one side the tie will be tapered along one edge while remaining straight along its opposite edge until the narrow neck portion is reached, the edges of which will be knitted in parallelism, after the knitting of which neck portion, by gradually throwing into operation certain needles one edge of the tie will be tapered while the other remains straight until the opposite end of the tie is provided with a flaring portion. The take up or tension means is necessary to give tension to the tie along one side thereof, or otherwise the stitches or loops at that side of the machine would interfere with one another by reason of their looseness, and therefore the greatest tension must be on that side where the loops would otherwise be loose, for these loose loops would tend to back up on the needles and prevent the proper operation of the machine, so that greater tension is placed upon one side of the tie than on the other. During the knitting of the tie the stripes apparently are located parallel with the top of the needle bed, as shown in Fig. 8. When, however, this tie is taken out and properly shaped the ornamental bars are in a true or substantially true bias position, and this without the necessity of stretching the tie out of shape, so that there is no tendency of the tie after it is finished to curl or assume any other position than that shown in Fig. 9.

By this improved process we are able to provide a tie of either one or more colors, that is either a plain or iridescent effect, having stripes shot thereinto of a different color or colors, and which stripes are located on a true or substantially true bias obtained during the knitting and without the necessity of stretching the tie after it is made to give this result, and in which all of the threads are of substantially the same tightness or looseness throughout the tie, and some of which stripes may be of a particular design, as for instance having a lace effect either of the same or a contrasting color or colors to the body of the tie.

By this improved process the entire tie from end to end thereof is knitted on a bias so that the thread loops are located on a true

or substantially true bias, and unravel on such bias while the fabric has the appearance of being made up of lengthwise or longitudinally extending wales and horizontal thread courses.

5. We claim as our invention:

1. The process of knitting which consists during the knitting of the fabric in causing the thread loops or stitches of one set of needles to be racked or shogged relatively to the thread loops or stitches of another set of needles and during the knitting placing the work under a differential tension, thereby providing a knitted fabric having the thread loops thereof located on a true or substantially true bias and then during the knitting of an ornamental portion of such fabric racking or shogging one set of needles in a different manner.

20. 2. The process of knitting which consists during the knitting of the fabric in causing the thread loops or stitches of one set of needles to be racked or shogged relatively to the thread loops or stitches of another set of needles and during the knitting placing the work under a differential tension, thereby providing a knitted fabric having the thread loops thereof located on a true or substantially true bias, and during the knitting feeding into the work at a predetermined time a thread or threads of a contrasting color to form knitted ornamental open mesh bias work, and for the purpose of knitting such ornamental open mesh bias work, racking or shogging one set of needles in a different manner.

30. 3. The process of knitting which consists in causing the thread loops or stitches of one set of needles to be racked or shogged to one side, and then to the other side of the thread loops or stitches of another set of needles to form the body of the work, and then at a certain interval feeding into the work a thread or threads to form a bias stripe, and during such feeding causing the thread loops or stitches of one set of needles to be racked step by step to one side, and then step by step to the other side of the thread loops or stitches of another set of needles, and during the knitting placing the work under a differential tension.

45. 4. The process of knitting which consists in causing the thread loops or stitches of one set of needles to be racked first to one side, and then to the other side of the thread loops or stitches of another set of needles, then during such knitting feeding into the work at a predetermined time a thread or threads of a contrasting color or colors to form a bias stripe, and then feeding into the work at a predetermined time a thread or threads to form a bias stripe of a different formation, and during such last feeding racking the thread loops or stitches of one set of needles step by step to one side and

then to the other side of the thread loops or stitches of another set of needles, and during the knitting placing the work under differential tension.

5. The process of knitting neckties and scarfs having substantially true bias stripes therein of different formation, which consists during the knitting of a portion of the tie in causing the thread loops or stitches of one set of needles to be racked or shifted alternately in opposite directions to the sides of thread loops of another set of needles; then during the knitting of another portion of the tie causing the thread loops or stitches of one set of needles to be racked a plurality of steps alternately in opposite directions to the side of the thread loops or stitches of another set of needles; then during the knitting of the tie feeding into the work a thread or threads of the bias stripe to be made, and during the knitting of the tie placing the same under a differential tension.

6. The process of knitting neckties and scarfs having substantially true bias stripes therein of different formation, which consists during the knitting of a portion of the tie in causing the thread loops or stitches of one set of needles to be racked or shifted alternately in opposite directions to the sides of thread loops of another set of needles; then during the knitting of another portion of the tie, causing the thread loops or stitches of one set of needles to be racked a plurality of steps alternately in opposite directions to the side of the thread loops or stitches of another set of needles; then during the knitting of the tie feeding into the work a thread or threads of the bias stripe to be made, and during the knitting of the tie placing the same under a differential tension, greater along one side thereof than along the other, according to the direction in which the said bias stripes run.

7. The process of knitting neckties and scarfs having substantially true bias stripes therein, which consists in first knitting the wide portion of the tie and gradually withdrawing certain needles, thereby to taper the tie to the neck portion thereof, and then knitting the same with its edges in substantial parallelism, then during a portion of the knitting of the tie causing the thread loops or stitches of one set of needles to be racked alternately in opposite directions to the sides of the thread loops or stitches of another set of needles; then during the knitting of another portion of the tie causing the thread loops or stitches of one set of needles to be racked a plurality of steps alternately in opposite directions to the sides of the thread loops or stitches of another set of needles; and during such knitting feeding into the work a thread or threads of a contrasting color or colors to form bias stripes,

and during the knitting of the tie placing the same under a differential tension.

8. The process of knitting a fabric having the thread loops thereof located on a bias and having therein a plurality of stripes of different formations located on a bias, which consists during the knitting of the body of the fabric in causing the thread loops or stitches of one set of needles to be racked in one way relatively to the thread loops or stitches of another set of needles, and at intervals feeding into the fabric a thread or threads of a contrasting color to form the stripe; then during the formation of the other form of stripe and during the feeding of the thread therefor into the work racking the thread loops or stitches of one set of needles in a different way relatively to the thread loops or stitches of another set of needles, and during the knitting placing the work under a differential tension.

9. The process of knitting a fabric having the thread loops thereof located on a bias and having therein a plurality of stripes of different formations located on a bias, which consists during the knitting of the body of

the fabric in causing the thread loops or stitches of one set of needles to be racked in one way relatively to the thread loops or stitches of another set of needles, and at 30 intervals feeding into the fabric a thread or threads of a contrasting color to form the stripe; then during the formation of the other form of stripe and during the feeding of the thread therefor into the work racking 35 the thread loops or stitches of one set of needles in a different way relatively to the thread loops or stitches of another set of needles, and during the knitting placing the work under a differential tension, the first 40 said racking being one step alternately in opposite directions; the second said racking being a plurality of steps first in one direction and then in another.
